Inventor:

Elijah Lindsley

United States Patent Office.

ELIJAH LINDSLEY, OF NEENAH, WISCONSIN.

Letters Patent No. 82,011, dated September 8, 1868.

IMPROVEMENT IN FANNING-MILLS.

The Schedule referred to in these Letters Patent and making part of the same.

TO ALL WHOM IT MAY CONCERN:

Be it known that I, ELIJAH LINDSLEY, of Neenah, in the county of Winnebago, and in the State of Wisconsin, have invented certain new and useful Improvements in Grain-Fans; and do hereby declare that the following is a full, clear, and exact description thereof, reference being had to the accompanying drawings, and to the letters of reference marked thereon.

The nature of my invention consists—

First, in bending the sieves and raising the rear ends thereof, by which arrangement the grain can be cleaned much better and much faster than with the straight or common sieve.

Second, in attaching a fine screen to the shoe which holds the sieves, under the sieves, said screen being shorter than the sieves, and connected at its front end with the screen-board.

Third, in attaching a shorter screen under the screen-board, and providing said bottom screen with a spout, for the purpose of carrying the grain out at the side of the mill, by which arrangement the grain is at once deposited into bags, without falling to the ground or floor, thereby saving one-half of the labor in cleaning grain.

In order to enable others skilled in the art to make and use my invention, I will now proceed to describe its construction and operation, referring to the annexed drawings, which form a part of this specification, and in which—

Figure 1 is a perspective view of the machine.

Figure 2, a perspective view of the shoe with its attachments.

Figure 3, a rear view of the shoe.

Figure 4, a front view of the same; and

Figure 5, a cross-section of the shoe, showing the position of sieves, screens, &c.

A represents a frame, made of suitable material and of any size required, the rear end of which is cylinder-shaped, to allow a fan to revolve in the same.

This fan consists merely in a shaft, which has its bearings in the sides of the frame, and is provided with arms on which slats are secured. The fan is turned by means of a crank, C, and gear-wheel D, on the side of the frame A.

In the rear end, and inside of the frame, the shoe a is hung, by means of hooks h h at each side thereof. This shoe consists of side-pieces, shaped as shown in fig. 5, with a cross-piece at the lower end, connecting the same.

Between the sides of this shoe, and secured thereto, are the sieves, b and c, the rear ends of which are bent upwards, as shown in fig. 5. These sieves may be constructed of any suitable material, with such apertures as to allow the grain to pass through, but the upper sieve should have larger apertures than the lower, so that some chaff, &c., which passes through the upper will not pass through the lower sieve.

Under the lower sieve, c, is a wire screen, d, placed, which is also attached to the sides of the shoe a, in such a manner that it inclines slightly forward, not extending as far forward as the said sieves, and connected at its front end with the screen-board e, which inclines towards the rear of the mill.

Cockle or other foreign matter passes through the screen d and falls on the screen-board E, out under the mill, while the grain rolls off said screen, the apertures therein not being large enough to allow it to pass through, and falls on to another wire screen, f, placed between the lower edges of the shoe a, and is fastened to the cross-piece connecting the sides thereof, the wire board e also being fastened to said cross-piece, and thus forming a funnel or hopper for the grain.

The grain, after falling on this short screen, f, passes out through the spout g, which protrudes through an opening in the side of the frame A. Around this hole or opening is some arrangement for hanging a bag, so that the grain will pass at once into the same, without falling to the ground or floor.

A rod attached to the lower end of the shoe, and passing around a cam-wheel on the shaft of the fan in the front part of the machine, jars the shoe, so that the grain will pass through the sieves without clogging, and the said fan blows all dust, &c., away from the grain.

Having thus fully described my invention, what I claim as new, and desire to secure by Letters Patent, is—

1. The sieves *b* and *c*, when bent as described, and operating as and for the purposes herein set forth.
2. The screen *d*, in combination with the sieves *b* and *c*, when constructed and operating as and for the purposes herein set forth.

In testimony that I claim the foregoing, I have hereunto set my hand, this 11th day of May, 1868.

ELIJAH LINDSLEY.
